United States Patent Office

Des. 195,255
Patented May 21, 1963

195,255

CHAIR

Francis L. Elliott, 525 S. Spring St., and Donald H. Bernhardt, 5118 Memory Lane, both of Evansville, Ind.

Filed Feb. 12, 1962, Ser. No. 68,768

Term of patent 14 years

(Cl. D15—1)

FIG. 1 is a side view of the chair;
 FIG. 2 is a rear view of the same;
 FIG. 3 is a front elevational view thereof, and
 FIG. 4 is a top plan view.
 In FIGURES 1-4 a dotted line indication of a tray is included therein for illustrative purposes only.

We claim:
 The ornamental design for a chair, substantially as shown and described.
